United States Patent

Des. 238,554
Patented Jan. 27, 1976

238,554

BOTTLE

John Pardo, Yonkers, N.Y., assignor to The Procter & Gamble Company, Cincinnati, Ohio

Filed Aug. 12, 1974, Ser. No. 496,582

Term of patent 14 years

Int. Cl. D9—01

U.S. Cl. D9—116

FIG. 1

FIG. 2

FIG. 3

FIG. 4

FIG. 5

FIG. 1 is an elevational view of a bottle showing my new design.

FIG. 2 is an elevational view thereof as seen from either side of FIG. 1.

FIG. 3 is a cross sectional view thereof taken on the line 3—3 of FIG. 1.

FIG. 4 is a bottom plan view thereof; and

FIG. 5 is a top plan view thereof.

I claim:

The ornamental design for a bottle, as shown.
